To all whom it may concern:

Be it known that I, Max S. Karp, a citizen of the United States, residing at 6106 Tenth Avenue, Los Angeles, in the county of Los Angeles and State of California, have invented a new, original, and ornamental Design for Coffee Table or Similar Article, of which the following is a specification, reference being had to the accompanying drawing, forming part thereof.

Fig. 1 is a perspective view of a coffee table or similar article, showing my new design.

The dominant feature of the design comprises translucent blocks disposed at the ends and rear of the article and serving to space the top from the base of the article. The rear surfaces of the translucent blocks which form the rear wall of the design are substantially flush with the rear edges of the blocks at the ends.

I claim:

The ornamental design for a coffee table or similar article, substantially as shown and described.
